(57) **CLAIM**

The ornamental design for an automotive message display, as shown and described.

DESCRIPTION

FIG. 1 is a front elevation view of an automotive message display showing my new design;

FIG. 2 is a rear elevation view;

FIG. 3 is a side elevation view;

FIG. 4 is a top plan view;

FIG. 5 is a bottom plan view; and,

FIG. 6 is a right side isometric view of an automotive message display showing my new design.

The break lines in the cord indicate no specific length.
